UNITED STATES PATENT OFFICE.

CHARLES A. LEONARD, OF EVE, MISSOURI.

HARNESS-HOOK.

No. 855,464.

Specification of Letters Patent.

Patented June 4, 1907.

Application filed November 12, 1906. Serial No. 342,984.

To all whom it may concern:

Be it known that I, CHARLES A. LEONARD, a citizen of the United States, residing at Eve, in the county of Vernon and State of Missouri, have invented certain new and useful Improvements in Harness-Hooks, of which the following is a specification, reference being had therein to the accompanying drawing.

10 My invention relates to improvements in hooks for suspending harness and other articles or objects; and it consists in the novel construction, combination and arrangement of parts hereinafter described and claimed.

15 The object of the invention is to provide a simple and practical hook of this character, which, when not in use, may be swung against the wall or other support on which it is mounted and thus be out of the way.

20 The above and other objects, which will appear as the nature of the invention is better understood, are accomplished by the construction illustrated in the accompanying drawings, in which,

25 Figure 1 is a perspective view of my improved foldable harness hook; Fig. 2 is a vertical section through the same; Fig. 3 is a detail horizontal section taken on the plane indicated by the line 3-3 in Fig. 2; and 30 Fig. 4 is a perspective view of the upper end of the hook, showing its spring engaging block removed.

In the practice of the invention, I preferably make the hook 1 of a piece of metal rod 35 by bending the latter upon itself to provide upper and lower arms 2, 3, which have downwardly bent ends 4, 5, disposed in longitudinal alignment with each other so that they may be concentrically pivoted in a bracket 40 or support 6. The latter is in the form of a metal plate, preferably of rectangular form and flat so that it may be secured upon a wall or other support by screws or similar fastenings passed through apertures 7 formed in it, as clearly shown in Fig. 1. 45 Adjacent to the lower end of the plate 6 is provided upon its front a laterally or horizontally projecting lug 8, formed with an aperture to receive the end 5 of the hook and 50 thus provide a pivot bearing for the same. At the upper end of the plate 6 is provided a similar, but larger lug or projection 9 which is also apertured as at 10 to receive the upper end 4 of the hook and to provide 55 a pivotal bearing for it. This end 4 of the hook has a cylindrical portion 11 which pro-

jects from and is adapted to rotate in the bearing opening 10, and it is also formed with a reduced portion 12 of square or other polygonal form in cross section. Upon the 60 squared end 12 is removably secured by means of a set screw or the like 13, a block 14 preferably of rectangular form, as shown. The block 14 is adapted to bear against a flat or leaf spring 15 which has one of its 65 ends secured by a screw 16 to a support 17 and its free end 18 engaged with a similar support 19. These supports 17, 19 are preferably in the form of blocks which space the spring from the bracket plate 6 and hold it 70 in engagement with the block 14. They may be formed integral with the plate 6 or separate, as shown, and secured thereto by rivets or similar fastenings 20, as indicated in dotted lines in Fig. 3. The outer faces of 75 said supporting blocks 17, 19 are recessed, as shown at 21 to receive the ends of the spring and prevent the same from shifting from its transverse position.

The construction, operation and advantages of the invention will be readily understood from the foregoing description taken in connection with the accompanying drawing. It will be understood that when the hook 1 is swung outwardly at right-angles to the plate 80 6, as shown in full lines in Fig. 1, the flat rear face of the block 14 will be engaged by the spring 15 so that said hook will be retained in such position, and that when the hook is swung to either side into a position parallel 85 with the plate 6, as shown in dotted lines in Fig. 1, one of the flat sides of the block 14 will be moved into engagement with the spring, and the hook will thus be retained in its folded 90 position. By mounting the hook in this manner so that it may be swung against the wall or other support on which it is mounted, it may be quickly and easily thrown out of the way when its use is not desired. 95

It will be observed that the block 14 serves 100 two purposes, namely that of retaining the end or pintle 11 in the bearing lug 9 and thus preventing the hook from being casually displaced from the attaching plate, and that of providing comparatively large flat surfaces 105 for engagement with the spring 15 whereby the hook will be effectively retained in either its folded or angular position. The provision of the block 14 also enables the hook to be formed of comparatively light wire so that 110 the device may be produced at a comparatively small cost.

Having thus described my invention, what I claim as new and desire to secure by Letters Patent of the United States, is:—

1. A device of the character described comprising an attaching plate having apertured bearing lugs, a hook having longitudinally alined downwardly projecting ends or pintles for engagement with said bearing lugs, one of said pintles projecting through and extending beneath its bearing lug, a flat spring mounted upon said plate, and a block removably secured upon said projecting end of the pintle for retaining the latter in its bearing lug, said block having flat faces to engage said spring whereby the hook is held either in its folded or angular position, substantially as described.

2. A device of the character described comprising an attaching plate having upper and lower vertically alined apertured bearing lugs, a hook made from a single piece of wire to form an upper longitudinal arm, a lower inclined arm and upper and lower longitudinally alined and downwardly projecting ends or pintles adapted to engage the apertures in said bearing lugs, one of the ends or pintles of said hook projecting entirely through its bearing lug and having a flat face, a block

removably secured upon the flat face of said projecting end of the pintle for retaining the latter in its bearing lug, said block being formed with flat faces, and a flat spring mounted upon said plate and adapted to bear against the flat faces of said block for holding the hook in either its folded or angular position, substantially as described.

3. A device of the character described comprising an attaching plate having apertured bearing lugs, a hook having upper and lower ends in longitudinal alinement to engage the apertures in said bearing lugs, one end of said hook having a polygonal shaped portion, a block having flat sides and an opening to receive said polygonal-shaped portion of the hook, a set screw for retaining said block upon the hook, recessed supports upon said plate, and a flat spring mounted in said recessed supports and adapted to engage the flat faces of said block, substantially as shown and for the purposes specified.

In testimony whereof I hereunto affix my signature in presence of two witnesses.

CHARLES A. LEONARD.
